REINFORCED CONCRETE POST

William H. Wascher, Flint, Mich.

Application January 29, 1944, Serial No. 520,150

3 Claims. (Cl. 72—85)

This invention relates to a method of forming reinforced concrete posts and a post formed thereby, the principal object being the provision of a post of this type of superior characteristics and to a simple and efficient manner of making the same.

Objects of the invention include the provision of a concrete post having a metallic reinforcement located therein, the connection between the concrete and the reinforcement being such that relatively different expansive and contractive movement of the reinforcement and the concrete will not rupture the concrete; and the provision of reinforced concrete posts in which the reinforcement is surrounded by the concrete and a yieldable coating is provided between the reinforcement and the concrete whereby to mitigate the strains imposed on the concrete due to changes in the relative dimensions of the concrete and the reinforcement due to changes in temperature.

Other objects include the provision of a method of making reinforced concrete posts by means of which the reinforcements are positively located in the form for the concrete consistently in a predetermined position with respect to the exterior faces of the concrete; the provision of a method of forming reinforced concrete posts in which sleeves provided in the posts for passage of securing bolts or screws into the reinforcement in the final product provide means cooperating between the reinforcement and the form for the post to positively lock and locate the post within the form during the concrete pouring operation; and the provision of a method as above described in which bolts, corresponding to those employed in connection with the finished post are employed between the form and the reinforcement and pass through such sleeves to positively locate the reinforcement within the posts.

The above being among the objects of the present invention the same consists in certain novel features of construction, combinations of parts, and steps of operation to be hereinafter described with reference to the accompanying drawing, and then claimed, having the above and other objects in view.

In the accompanying drawing which illustrates a suitable embodiment of the present invention and in which like numerals refer to like parts throughout the several different views,

Fig. 1 is a side elevational view of a reinforced concrete post constructed in accordance with the present invention illustrated as having one end

thereof imbedded in the ground and supporting a portion of a wire fence which is clamped thereto;

Fig. 2 is an enlarged vertical, sectional view taken centrally through a post of the construction shown in Fig. 1 and as located within the form in which the concrete of the post is cast; and,

Fig. 3 is an enlarged transverse, sectional view taken on the line 3—3 of Fig. 2 to better illustrate the construction.

The present invention relates to reinforced concrete posts or the like and to a new and novel method of forming the same. Reinforced concrete posts have heretofore been proposed and made but they have incorporated disadvantages which, as far as I am aware have not heretofore been overcome. For example, a common trouble with reinforced concrete posts as heretofore constructed has been that due to variations in dimensions of the reinforcement and the concrete due to temperature changes it is a usual occurrence of a concrete to crack, and once the concrete has cracked particularly through the thickness thereof the strength of the post is obviously materially reduced. Where the reinforcement is brought relatively close to one end of such post but is otherwise concealed or completely imbedded in the concrete, relative expansion and contraction of the concrete and the reinforcement commonly causes the relatively thin concrete end covering to be cracked off, thus exposing the metallic reinforcements to the effects of the weather and as such reinforcements are usually made of iron or steel, subsequent discoloration of the concrete results.

In accordance with the present invention the above described difficulty of the prior art constructions is obviated by providing the metallic reinforcement before it has been cast in the concrete with a relatively heavy coating of tar, asphalt or other similar material having a relatively low melting point which, while remaining in a solid or semi-solid state at the highest atmospheric temperatures commonly met with, yet is sufficiently yieldable at the coldest atmospheric temperature to which the post may be commonly exposed to permit a slight amount of relative sliding movement between the concrete and the reinforcement during relative changes in the length thereof due to the atmospheric temperature changes. In other words, this coating on the reinforcement and separating it from actual physical contact with the concrete, or substantially separating it, will yield under stresses ma-

terially less than that required to fracture the concrete and thus prevent the relative change in dimensions due to temperature changes from cracking the concrete as in prior art constructions. Furthermore, in accordance with the present invention nuts are welded to the reinforcement and sleeves are provided extending between the exterior face of the post and the reinforcement in line with each nut so that a screw, bolt or other threaded element may be projected through the sleeve and threaded into the nut for the purpose of securing some desired part such as a fence wire, mail box, or the like to the post.

In the broader aspects of the invention the reinforcement may be metal of any suitable cross-sectional configuration such, for instance, as I-beams, angles, T-sections, or the like, but I prefer to form such reinforcements from metal tubes or pipes as this section ordinarily provides the maximum rigidity for the amount of metal employed. Additionally large amounts of scrap pipe are available for use at a relatively low cost and which are readily adaptable for use in constructing posts in accordance with the present invention. For the latter reason the reinforcement is shown in the drawing as being of pipe-like form and although reference may be herein-after made in the specification and claims to pipes the obvious substitution of other sections in place thereof will be made apparent to those skilled in the art and constitute an equivalent thereof.

Referring to Fig. 2 in which the structure of the concrete post is shown although contained within the form or mold in which it is made, it will be observed that it comprises a metallic pipe 10 which is molded centrally within a surrounding layer 12 of concrete. It will be appreciated that the pipe 10 in accordance with the present invention is provided with a surrounding coating 14 of tar or the like of a character previously described which serves to maintain the pipe 10 out of substantial contact, or at least out of direct adhering relation, with respect to the concrete 12 itself. The pipe 10 projects downwardly preferably to a point below the lower end of the concrete 12, or at least is exposed at the lower end of the post, and preferably terminates a material distance short of the upper end of the concrete as shown. Preferably in order to keep material amounts of concrete out of the interior of the pipe 10 during the molding operation, although not necessary in all cases, a wooden or other plug such as 16 is received in the upper end of the pipe 10.

At desired intervals over the length of the pipe 10 nuts 18 are welded thereto. These nuts 18 are also coated with the tar or the like 14, and preferably with a heavier coating than on the pipe 10. In line with each nut 18 a sleeve 20, preferably of metal and of an internal diameter preferably greater than the diameter of the threaded bore of the nuts 18, is extended concentrically with the hole in the corresponding nuts 18, from the nuts 18 to the outer surface of the post. These sleeves 20, therefore, provide openings through which screws, bolts or the like such as 22 in Fig. 2 and at 24 in Fig. 1 may be projected into threadable engagement with the nuts 18 for the purpose of securing some desired part or device to the post. Preferably the bores of the sleeves 20 are larger than the diameter of the bolts 22 so that during relative expansion or contraction of the pipe 10 and concrete 12 the screws 22 or 24 will not act to transmit the

force of the movement between the pipe and the concrete.

In practice bolts or screws such as 22 or 24 may be associated in any suitable way with the device which is to be supported by the post and such screws or bolts projected through the sleeves and into the nuts 18 for the purpose of securing such device to the posts. For instance in Fig. 1 it is assumed that a wire fence 26 is to be supported by the post which is here designated generally at 28. To accomplish this the wire fence 26 is supported in flat relation against that side of the post through which the screws 24 may be projected, a clamping bar 30 is placed over the outside face of the wire fence 26 into parallelism with the post 28 and then the screws 24 are projected through the clamping bar 30 and threaded into the corresponding nuts 18 until the clamping bar 30 securely clamps the wire fence 26 against the post 28. Thus the wire fence is securely clamped in position to the post.

It will be appreciated from the above that the pipe 10, which, of course, will expand and contract to a greater degree than the concrete 12 due to temperature changes may, because of the coating 14, move relative to the concrete. Because it is exposed at the bottom of the post through the concrete, and preferably projects therefrom, these expansion and contraction movements of the pipe 10 may occur without subjecting the concrete to any more stress than is required to flow the tar or the like coating 14, and the concrete is, therefore, relieved of any stresses because of such movements that are sufficiently great to rupture it. Although the nuts 18 more or less interlock the pipe 10 and concrete against axial movement, flowing of the coating 14 on the nuts permits sufficient relative movement to minimize the stresses that would otherwise occur. The post is, therefore, capable of withstanding relatively great changes in length due to temperature changes without rupturing the concrete.

In forming reinforced concrete posts there is, of course, always a problem in connection with the consistent proper location of the reinforcement in the final product. In accordance with the present invention this predetermined position of the pipe 10 within the center of the concrete 12 is readily and positively taken care of. In the manufacture of the post described a form or mold of the desired cross-sectional configuration of the final post is provided. In the present case it is assumed that it is desired to provide a post of substantially rectangular cross-section but in which the corners of the square are beveled off. The form itself may be made of metal or of wood or of any other suitable material but for the purpose of illustration it is shown in the accompanying drawing as being formed of wood. In other words, it is shown as being formed of four strips or sections of wood, 32, 34, 36 and 38, each of a length corresponding with the length of the post desired and arranged to form a hollow square, the sections 34 and 36 being rigidly interconnected with each other as are the sections 32 and 38, the meeting edges of the sections 32 and 34 being hinged together as at 40 so that the two sections thus formed may be hinged outwardly away from each other as indicated by the dotted lines in Fig. 3.

In the corners of the hollow form thus provided and in order to provide for the beveled corners of the post, triangular strips 42 are secured, in the case of the strips 42 between the sections

32 and 38 and between the sections 34 and 36 to both the abutting sections, and in the case of the strips 42 between the sections 32 and 34 and between the sections 36 and 38 to one of the sections only so as not to interfere with the pivoting action of the two parts of the form.

At the free meeting edges of the sections 36 and 38 at a plurality of transversely aligned points over the length thereof brackets 44 and 46 are secured in spaced relation to the member 36 and member 38, respectively. The brackets 44 and 46 are formed from short pieces of angles, one flange of each of which is secured in flat contacting relation with respect to its corresponding section 36 or 38 and the remaining flanges of which project outwardly into spaced and parallel relationship with respect to each other as indicated in Fig. 3.

A rod 48 is extended between each cooperating pair of brackets 44 and 46. The outer end of each bracket 44 is slotted so as to permit the corresponding end of the rod 48 to be laterally projected thereinto and the rod 48 is provided with a head 50 overlying the outer or upper face of the bracket 44 as shown in Fig. 3. The rod loosely projects through the bracket 46 so as to be capable of a relative pivotal or swivable movement with respect thereto and on such projecting end has pivotally or rotatably secured thereto a cam element 52 provided with an operating handle 54. The arrangement is such that when the operating handle 54 and cam 52 are turned to the position illustrated in Fig. 3, the cam 52 in bearing against the bracket 46 and acting through the rod 48 and bracket 44 clamps the free edges of the members 36 and 38 securely together. When the cam 52 is rotated in a clockwise direction from the position shown in Fig. 3, then the clamping force between the members 36 and 38 is relieved and the head 50 of the rod 48 may be swung out of the notch in the bracket 44 upon which the two sections of the form may be swung apart as illustrated by dotted lines in Fig. 3, in which position a completed post may be removed from the form.

In positioning the pipe 10 in the form thus described the lower end of the pipe is received in a relatively closely fitting central opening 56 in a block 58 which is removably received in the lower end of the form as illustrated in Fig. 2, the block 58 being externally shaped in complementary relationship to the internal surfaces of the form at this end of the same so as to provide a closure. The pipe 10 projects upwardly centrally of the form as indicated. The nuts 18 are welded or otherwise secured to the pipe 10 prior to the positioning of the pipe 10 in the form and it will be observed that the pipe 10 is preferably provided with diametrically disposed holes 60 in line with each nut 18 so that screws or bolts such as 22 may project into or through the pipe 10 if necessary.

The form is provided with openings 62 in line with each of the nuts 18 and a bolt such as 22 is projected through each of these openings, through the collar 20 which is to be associated with the corresponding nut 18 and which may be slipped over the bolt at this time, and then threaded into the nut 18 until the collar 20 is clamped between the form and the nut 18. The collars 20 are made of such length that when thus clamped between the form and the corresponding nut 18 the pipe 10 will be positively located at a predetermined distance from all the walls of the form and thus centrally of the forms if

this particular relation of the reinforcement is desired. The various screws 22 and sleeves or collars 20 cooperate between the form and the reinforcements to positively locate the latter in the form.

Preferably although not necessarily the upper end of the pipe 10 is provided with a plug or closure 16 and it will be observed from Fig. 2 that the form is extended upwardly beyond the upper end of the pipe 10 to the extent desired in order to provide a wall of suitable thickness over the upper end of the pipe.

It will, of course, be appreciated and as previously explained that before the pipe 10 is inserted in the form it and the nuts 18 are provided with an external coating of tar or the like.

The pipe 10 thus having been coated and positively located in the form, the form is then filled with concrete and after the concrete has set sufficiently the clamps including the cam 52 are loosened and one of the form sections pivoted away from the other form section, as shown by dotted lines in Fig. 3, the screws or bolts 22 are removed, and the thus completed post lifted out of the form. The end member 58 is then removed, leaving the post in completed condition. It will be observed that the lower end of the pipe 10 will thus project below the concrete while the upper end of the pipe is covered over by a layer of concrete. In practice and as previously pointed out the lower end of the post is imbedded in earth or other suitable material and any desired object may be secured to it by screws such as 22 or 24 either with or without the use of auxiliary clamping devices.

Because of the coating 14 on the reinforcement 10 and because the lower end of the pipe 10 is exposed at the bottom end of the post, when the concrete 12 and the reinforcement 10 expand or contract at different rates longitudinally of the post the coating 14 will yield and prevent any substantial stress being applied to the concrete which would tend to crack and break it loose as so often occurs with prior art devices. Thus the concrete is enabled to remain as a single integral piece of material which may be utilized to the full extent of its strength in resisting bending or the like and which cannot be realized if it is cracked or broken. In order to enable this last feature to be completely realized it will be appreciated that the sleeves 20 should more or less loosely fit the bolts or screws 22 or 24 which project therethrough and thus provide clearance between the screws and the concrete during relative contractive or expansive effects of the reinforcement and with respect to the concrete 12.

Having thus described my invention, what I claim by Letters Patent is:

1. A reinforced concrete post comprising, in combination, an elongated metallic reinforcement member, concrete surrounding said reinforcement member and imbedding the same therein, and a layer of tar-like material interposed between said concrete and said reinforcing member, at least one end of said reinforcing member being exposed and free of restraint at the corresponding end of said post whereby it may extend from or withdraw into said concrete during elongation and contraction thereof, respectively, due to temperature changes, due to yielding of said layer.

2. A reinforced concrete post comprising, in combination, an elongated reinforcement member, nuts fixed to a side of said member, a layer of tar-like material surrounding said member and

said nuts, a mass of concrete surrounding said member and said nuts, said concrete being provided with openings therein extending from an exterior face thereof to each of said nuts, and a hollow member lining each of said openings.

3. A reinforced concrete post comprising, in combination, a metallic reinforcement in the form of a pipe, the length approximately equal to that of said post, a plurality of nuts welded to

said pipe in spaced relation with respect to each other axially of said pipe, a mass of concrete surrounding said pipe and imbedding the same therein, one end of said pipe projecting outwardly beyond said concrete, said concrete having holes therein communicating an outer face thereof with each of said nuts, and a sleeve lining each of said openings.

WILLIAM H. WASCHER.
